UNITED STATES PATENT OFFICE.

FRANK L. O. WADSWORTH, OF PITTSBURGH, PENNSYLVANIA.

WATER-HEATER CONSTRUCTION.

1,248,579.

Specification of Letters Patent.

Patented Dec. 4, 1917.

Application filed October 3, 1911. Serial No. 652,576.

To all whom it may concern:

Be it known that I, FRANK L. O. WADSWORTH, a citizen of the United States, residing at Pittsburgh, in the county of Allegheny and State of Pennsylvania, have invented certain new and useful Improvements in Water-Heater Constructions, of which the following is a specification.

The invention relates to improvements in water heaters and particularly to the automatic controlling mechanism for governing the supply of gas to the burners. The invention has for its objects; the provision of improved means for regulating the supply of gas to the burners of a heater by means of a combined water pressure and thermostatic controlling mechanism operating upon the principle as broadly disclosed in the British patent to Braithwaite No. 9598 of 1888. Several embodiments of the invention are illustrated in the accompanying drawings, wherein:

Figures 1 and 2 are front and side elevations respectively of the ordinary modern instantaneous heater, such as that shown in the patent to Shook No. 993,723, with my improvement applied thereto; Fig. 3 is a transverse section on enlarged scale through my controlling mechanism; Fig. 4 is a section through a modified type of controlling mechanism; Fig. 5 is a section through another modified type of controlling mechanism; Fig. 6 is a section through another modified type of controlling mechanism; Fig. 7 is a partial section through another modification differing slightly from the construction of Fig. 6; and Fig. 8 is a section through still another modified type of controlling mechanism.

Referring first to the general arrangement of the heater parts as shown in Figs. 1 and 2, A is the casing of the heater; B and C are the upper coils of the heater; D is a lower reverse coil connected to the upper coils by means of the pipe E; F are the burners mounted upon the usual burner ring; G is the gas supply pipe; H is the casing of the gas valve for controlling the supply of gas to the burners; I is a pipe leading from the gas valve to the burner ring; and K is the casing of the combined water pressure and thermostatic controlling mechanism wherein my invention particularly resides, it being understood that such

mechanism is of general application and is not to be regarded as restricted to use in connection with this particular type of heater illustrated.

Referring now to Fig. 3 in connection with Figs. 1 and 2, 1 is the cold water inlet leading to the upper coil B, and 2 is the hot water outlet leading from the lower inverted coil D, the controlling mechanism in the casing K being interposed between such inlet and outlet and so arranged that one side of the fluid-actuated member is exposed to the pressure of the liquid flowing into the heater, while the other side is exposed to the pressure of the liquid flowing out of the heater. The fluid actuated member is a piston 3 sliding in a cylinder 4, said cylinder being provided with an external water chamber 5, having two fluid connections 6 and 7, the first of which is in communication with the water supply main, and the other of which is connected up through the T 8 and the pipe 9 with the water inlet 1. The chamber 5 communicates with the left hand end of the cylinder 4 through a port 10, and communicates with the right hand end of the same cylinder through a port 11, which is normally kept closed by a valve 12. The piston 3 may be of any approved construction, but is preferably of the packing ring type, these rings being indicated by the reference numeral 13. The stem 14 of the piston 3 passes through a packing box 15 on the cylinder head 16, and is connected by a link 17, with the stem 18 of a gas valve 19. This gas valve 19 controls the passage of the fuel from the inlet gas pipe G to the supply gas pipe I, which passes to the heating burners. The same casting which supports these various parts already described may be utilized to support the plug of an ordinary gas cock 22, for completely shutting off the gas when the heater is not in commission. The gas valve chamber may be further provided with the ordinary auxiliary connection 23 leading to the pilot light which is used to ignite the gas supplied intermittently to the main burners through the automatically controlled valve 19.

In order to eliminate the necessity for using a stuffing box around the gas valve stem I provide the valve head 19 with a central recessed boss, which, when the valve is lift-

ed from its seat, engages with a washer 20 on the valve box head and thus seals the opening around the stem 18. The opening around the stem 14 is similarly sealed—when no water is flowing—by a washer 21 secured to the cylinder head 16 and engaging with a central opposing boss on the piston member 3. The only leakage of water which can occur through the stuffing box 15, takes place when the water is flowing and the piston member 3 is moved away from the head 16. As this occurs only at infrequent intervals, the stuffing box 15 may be left quite loose, thus greatly reducing the friction on the stem 14 and avoiding any danger of the parts sticking in the opened position. In order to insure the seating of the piston boss against the washer 21 when the parts are in closed position, a certain amount of lost motion between the parts 3 and 19 is provided by slotting one end of the link 17, and a spring 19^a is provided to hold the valve 19 against its seat when the water actuated piston is in its normal left hand position.

The right hand end of the cylinder 4 also communicates through a port 24 with a rectangular water chamber 25 which is in communication through the elbow pipe 26, with the hot water outlet 2. Leading from this chamber is the thermostat chamber 27 in which is mounted the thermostat rod 28. This thermostat rod or tube is of zinc or copper or of some material having a greater coefficient of expansion than the material of the chamber 27 and is mounted on its upper end on a perforated collar 29, through which the hot water passes to the house supply pipe 30. The lower end of the thermostat rod or tube 28 passes through a perforated guide collar 31 and terminates in a knife edge which bears against the thermostat lever 32 which is mounted on posts 33 in the sides of the box 25. The long end of the lever 32 has a knife edge bearing on the second thermostat lever 34 which is mounted on an adjustable point bearing 35, and the outer end of the second thermostat lever 34 bears upon, but is not connected with the stem 36 of the valve 12 already described. The thermostat lever system is held in position against expansion of the thermostat rod by means of a spring 37, and the valve 12 is independently held in position by a second spring 38, the spring 38, valve 12, and stem 36, being all readily removed by unscrewing the cap 39. The parts of the thermostat mechanism can likewise be readily put in place or removed by taking off one side, 40, (Fig. 2) of the box 25, and the said parts may be adjusted in position from outside of the box by means of the adjustable screw support 35. If desired the upper end of the thermostat chamber 27, may be connected with the T 8 by means of a by-pass 41, in which case

the said T, 8, is provided with a spring controlled check valve (as described, for example, in Patent No. 993,723) of such construction that when no water is flowing into the inlet 1 from the pipe 7 the check valve 70 will be open allowing a free circulation of the water through the coils of the heater, the thermostat chamber 27 and the by-pass connection 41; but when water is being drawn off through the pipe 30 and correspondingly supplied through the pipe 7, the check valve will be closed, shutting off the communication of the inlet pipe 1 with the by-pass 41.

The operation of the automatic control mechanism just described is as follows: 80 When the temperature of the water in the heater is less than that at which the thermostat is set to operate the thermostat lever 34 will be retracted out of contact with the valve stem 36—as shown in Fig. 3—and the valve 12 will be closed, as already described by the action of the spring 38. If now the house outlet pipe 30 is opened, the pressure in the chamber 25 will be reduced by the out flow of the water below the pressure of the in-flowing water, this difference of pressure being established by the resistance to the passage of the liquid through the heating coils. There will thus be set up a difference in pressure on the two sides of the piston member 3, since the left hand end of the cylinder in which this piston member moves is in direct communication through the port 10, with the in-flowing water, while the right hand end of the piston chamber is in direct communication through the small port 24 with the out-flowing liquid. In consequence of this difference of pressure, the piston member 3 will be moved to the right, thus opening the gas valve 19 and allowing the fuel to flow directly to the main heating burners where it will be ignited by the pilot light. When the flow of water through the heater is stopped, the pressure of the liquid will of course at once equalize itself again— 110 since the difference of pressure at the inlet and at the outlet is kept up only by the flow of the liquid—and the piston member 3 will be restored to its initial position, thus closing the gas valve 19, by the unbalanced pressure of the fluid against the piston stem 14. This restoring pressure may be supplemented if desired by a spring 42, but this spring will be entirely unnecessary if the diameter of the stem 14 is made sufficiently 120 large. If, while the flow of water through the heater still continues, the temperature of the out-flowing water rises above a certain predetermined point for which the thermostat may be set, the expansion of the thermostat rod or tube 28 will force the thermostat levers 32 and 34 down until the latter contacts with the end of the valve stem 36 and opens the valve 12. The opening of this valve puts both ends of the cylinder 4 into 130

direct communication with the inflowing water, and equalizes the pressure on the two sides of the piston member 3 thereby allowing it to return to its first position and closing the gas valve 19 as just described. In order that this equalization of the pressure by the opening of the valve 12 may not be sensibly retarded by the presence of the port opening 24, the latter is made of considerably smaller area than the port opening of the valve 12. The opening of the latter valve in the manner above described has a further effect of allowing a small amount of cold liquid to pass directly from the chamber 5 to the chamber 25, and thence to the thermostat chamber 27, and the mixture of this cold water with the hot water in the thermostat chamber will aid in the quick reduction of the temperature of the out-flowing water, thereby preventing the overheating of the liquid by the so-called "lag" of the usual thermostatic control, and thereby hastening also the lowering of the temperature of the out-flowing water to a point at which the thermostat will cease to act and will permit the fuel supply to be turned on again by the water flow control of the mechanism. In consequence of this, and in consequence of the fact that a very small movement is necessary in order to open or close the valve 12, the temperature control of the above described device may be made very sensitive, that is to say, the gas may be turned off or on by the operation of the device by variations of only a few degrees in temperature of the out-flowing water. The size of the port opening 24, and consequent volume of flow of the cold water therethrough when the valve 12 is open, may be regulated if desired by a plug valve 43.

The various parts of the mechanism described may be conveniently supported in proper position one with respect to the other, and secured as a unit to the casing of the heater by means of a base plate 44, as clearly shown in Fig. 2.

Construction of Fig. 4.

In this construction 2' indicates as before the outlet from the coil or heating chamber of the apparatus and 6' and 7' indicate pipes corresponding to the like numbered parts of Fig. 1, said pipes leading respectively to the main water supply, and 5 to the cold water inlet 1 at the top of the heater. These two pipes are connected, as in the previously described apparatus by a passage-way 5' which communicates through a port 10' with the left hand side 60 of a circular diaphragm chamber 50. This diaphragm chamber is divided into two two parts by the diaphragm 51 which is preferably made of thin corrugated metal, the outer edges of which are clamped between the outwardly projecting flanges of

said chamber, and the center of which is clamped to the stem 14'. A spring 52 is interposed between the center of the diaphragm and the right hand wall of the diaphragm chamber, and serves to keep the diaphragm 51 normally deflected to the left as shown in Fig. 4. The right hand head of the diaphragm chamber is bored to receive a plunger valve which is made in two parts 53 and 54. These parts are held in adjustable relation one with respect to the other by means of a screw 55 threaded into the lower part 54, and a spring 49 interposed between the head of the screw 55 and the lower end of the part 53. Ready access to the interposed adjusting nut is secured by providing an opening 56 in the wall of the valve box, this opening being closed by a cap 57. The upper part 53 of the plunger valve is provided with a port 58 which is normally in communication with a port 24' opening into the right hand end of the main diaphragm chamber 50. The lower part 54 of the plunger valve is provided with a valve seat 12' which normally covers and closes the port 11' also leading into the right hand end of said diaphragm chamber. Communication between the space below the valve head 12' and the passage-way 5' is secured by means of a hole 59 through the flanged sides of the two halves of the diaphragm chamber 50. A spring 38' held in position by a cap 39' bears against the valve head 12' and keeps it normally placed tightly against its seat. The thermostat which I employ in this construction is a liquid thermostat consisting of a closed tube 60 filled preferably with some viscous liquid having a high temperature coefficient of expansion, such for example as glycerin or crude oil. Mounted concentrically in the lower end of this tube 60 is a smaller inner tube 61, and this tube is bored or reamed to receive a short metal plunger 62, which is made to fit the bore of the tube 61 very accurately. The upper end of this plunger is pointed or coned and just above this coned end there is a short length of leather or rubber 63 which serves as a self-adjusting packing ring. Above this packing ring is a mass of liquid mercury or fusible metal 64 which further serves to seal the opening between the plunger 62 and the liquid filling the tube 60. The upper end of the thermostat tube 120 is closed by an adjustable screw 65, the position of which serves to regulate the position of the plunger 62 for any given temperature of the liquid in the tube. Below the plunger 62, which does not extend down to the lower end of the tube 61, there is a second packing ring 66 of rubber or leather, and below this again is a second plunger 67 which bears directly against the recessed end of the upper part 53 of the plunger 130.

valve previously described. A stem 14' is connected to the diaphragm, and this stem operates a gas valve corresponding in structure to that in Fig. 3.

- 5 The operation of this mechanism is as follows: When the water in the heater is at rest, and its temperature is less than that at which the thermostat is set to act (by a joint adjustment of the screw 65 and the 10 nut 55) the parts are in a position shown in Fig. 4. When, under these conditions the flow of water through the heater is started, for example by opening a faucet in the outlet pipe from the heater, the pressure in the 15 thermostat chamber communicating with the outlet pipe will be reduced below the pressure at the inlet by the resistance to the flow of water through the heating chamber, and this will in turn set up a difference 20 in pressure in the right and left hand ends of the diaphragm chamber 50, which communicates through the port openings 24' and 58 with the out-flowing water, and through the port opening 10' with the in-flowing 25 water. The difference in pressure will move the diaphragm 51 to the right against the pressure at the spring 52, and will open the gas valve which is connected as before to the stem 14' of this diaphragm. When 30 the flow of water is stopped the pressure on two sides of the diaphragm will be at once equalized, and the diaphragm will be returned to the normal position shown in Fig. 4 by the reaction of the spring 52. If, while 35 water is flowing, the temperature rises above a certain predetermined point—dependent upon the setting of the thermostat parts—the liquid in the thermostat tube 60 will expand thereby moving the valve part 53 and 40 closing in part the port 24'. Further expansion of the liquid will bring the part 53 into contact with the screw 55 and the parts 53 and 54 will then move downwardly together thereby closing still further the port 45 24' and opening the port 11'. The opening of the port 11' allows the pressure on two sides of the diaphragm 51 to be equalized by the direct admission of the in-flowing water to the right hand diaphragm chamber 50 and this equalization of pressure permits the diaphragm 51 to be returned to the normal position shown in Fig. 4 in which the gas valve is closed and the fuel is shut off from the main burners. The closing in 55 whole or in part of the port 24' by the first action of the valve part 53 prevents, in this case, the flow of the cold water into the thermostat chamber. However, the parts 53 and 54 may be so adjusted with relation to each 60 other by means of the screw 55 that they will move in unison with each other and leave the port 24' full open at the time that the port 11' is opened. I can therefore in this case either prevent the cold water from 65 mixing with the hot water when the valve 12' is opened by the thermostat, or can permit this mixture to occur to any extent that may be desired.

Construction of Fig. 5.

70

In this construction 2² indicates as before the hot water outlet from the heater entering the thermostat chamber 27², and 6² and 7² likewise indicate as before the cold water connections leading from the water supply 75 main to the cold water inlet 1 of the heater (see Figs. 1, 2 and 3). These pipes 6² and 7² communicate with each other through a chamber 5², and in this chamber there is arranged a spring pressure check valve 70 so mounted as to open with the flow of water into the heater. The left hand side of this check valve chamber communicates through the ports 71 and 10² with the left hand end of the cylinder 4², in which the fluid pressure 85 operated piston member 3² is located. The right hand end of the valve chamber communicates through the ports 72 and 11² with the right hand end of the cylinder 4². A check valve 12² is mounted in the chamber 90 between the port openings 10² and 11², this latter check valve being connected to a stem 36² leading through a stuffing box 73 and provided at its outer end with an adjustable nut 74. The movement of the check valve 95 12² is in this construction effected by a negatively acting thermostat member which comprises a rod or tube 75 of zinc, copper or other material having a high coefficient of expansion and the second rod or tube 76 of 100 nickel, steel, porcelain or other material having a very small coefficient of expansion. The tube 75 is secured at its lower end, and the rod 76 is secured to the tube 75 at its upper end and bears at its lower end upon the adjustable screw 77 which is mounted in the short arm of the thermostat lever 78. The long arm of this thermostat lever is forked to straddle the stem 36² and make engagement with the adjustable nut 74, and the 105 thermostat parts are kept in operative engagement with one another by means of a spring 79, the tension of which can be adjusted by a screw 80. When the temperature of the liquid in the thermostat chamber 110 27² rises, the tube 75 will expand more rapidly than the rod 76, and the lower end of that rod will in consequence of this be lifted, allowing the long arm of the thermostat lever to move to the left under the pressure of 120 the spring 79. When the temperature of the liquid in the thermostat chamber falls, the reverse movement will occur. The stem 14² of the fluid operated piston member 3² is connected as before by a link 17² with the 125 stem 18² to the gas valve 19², and when the piston 3² moves to the right, the gas valve will be opened, allowing the fuel to flow through the pipe G, the plug valve 22, and the pipe I to the main burners of the heater. 130

It will be noted that the construction and operation of this gas valve like that of Fig. 3, is such that no packing box is required for the stem 18², for when the valve is closed, the gas is shut off from the opening around the stem and when the valve is opened the washer on its right hand side is pulled tightly against the flanged head of the valve chamber and the opening around the valve stem is thereby sealed. Similarly the opening around the stem 14² is sealed, when no water is flowing, by the stem washer 81 which is secured at its outer edges to the central boss of the piston 3² and bears at its center against the opposing boss of the cylinder head 16². A spring 82 interposed between the washer 81 and the piston head 3² insures the sealing of the opening around the stem 14² independently of slight variations in the relative positions of the parts connecting the piston 3² to the gas valve 19² and thus eliminating in this case the necessity of providing for any lost motion in the link connection 17² or for providing any separate spring to act directly on the gas valve 19². The various parts of this control mechanism are all mounted and held in proper adjustable relation one to the other on a flanged frame or casting 83 by means of bolts and cap screws 84 and 85.

In the construction just described, the differences of pressure which are set up on the two sides of the pressure operated piston member 3² are produced by the action of the spring check valve 70. This valve is provided with a small leakage port 86, so that when the water is not flowing through the chamber 5², the pressure in the chambers on the two sides of this valve, and consequently in the chambers at the two ends of the cylinder 4², will be equalized, and piston member 3², and the gas valve 19² connected thereto, will be held in the normal closed position shown in the figure, by the unbalanced pressure of the liquid against the head of the stem 14², and also if desired by an auxiliary spring 42. When the flow of water is started, the check valve 70 will be opened against the pressure exerted by the water on the stem of this check valve and by the restraining spring 87; and the flow of the water past the check valve against these pressures will establish a corresponding difference in pressure in the chambers on the two sides of said valve and in the chambers at the two ends of the cylinder 4², thereby moving the piston member 3² to the right and opening the gas valve 19². When the flow of water stops, the pressures in these various chambers will at once equalize themselves, and the piston member 3², and the gas valve 19² connected therewith will move to the left shutting off the fuel supply to the main burners. If, while the water is still flowing, the temperature in the ther-

mostat chamber rises to such a point as to allow the long end of the thermostat lever to come in contact with the nut 74, the check valve 12² will be opened by the pressure of the spring 79, and free communication thus established between the port 71, and the port 11² will immediately equalize the pressures in the two ends of the cylinder 4², thereby closing the gas port as before. In order to avoid interference with this equalization by the action of the port 72, the latter is made considerably smaller in area than the opening through the valve 12² and the port 11², and if desired, the stem of the check valve 12² may also be provided with a collar 88 which will close the port 72 as the check valve 12² opens. When the temperature falls, the thermostat lever 78 will be moved back out of contact with the nut 74 and the valve 12² will be closed by the unbalanced pressure of the water against its stem, and the difference of pressure established by the flow of water through the main check valve 70 will be once more set up on the two sides of the piston member 3² again opening the gas port 19².

Similarly in this construction—as in the ones already described—there is very little frictional resistance to the movement of any of the operating parts (because either packed pistons or diaphragms are used and because stuffing boxes can be eliminated or left very loose) no “sticking” of the water actuated member in its opened position is ever likely to occur unless the water should contain so much sediment as to be practically unusable. Even in such cases, the access of sediment to the operating parts may be guarded against by the use of screens 89 and 91 covering the port openings 71, 10² and 11². These screens and the valve parts 12², 88, etc., are readily removed and replaced by taking out the cap 90.

Construction of Figs. 6 and 7.

In the construction of the preceding figures the control mechanism has in each case been placed on the lower part of the heater shell near the hot water outlet terminal of the heater coils. In the construction shown in Figs. 6 and 7, the control mechanism is placed near the top of the shell in close proximity to the cold water inlet 1². In this case the cold water passes from the pipe 6² connected to the water main into a chamber 5³ which communicates through the port 10³ with the right hand end of the diaphragm chamber 50³, and thence directly to the cold water inlet 1². The hot water issuing from the heater coils enters the thermostat chamber 27³ at its lower end, passes upwardly through said chamber into the pipe 95, and thence into a chamber 96 which communicates with the left hand end of the diaphragm chamber 50³ through a port open-

ing 24^a, and finally enters the house service pipe 30^a. The thermostat is of the same construction as that shown in Fig. 5, and like that one is arranged to move the thermostat lever 97 positively to the left against the pressure of the springs 98 and 99 as the temperature falls. The diaphragm 51^a is preferably of thin corrugated sheet metal clamped into position between the two parts 10 of the diaphragm box, and is normally deflected to the right by the pressure of the spring 100. By the center of the diaphragm there is fixed a disk 101 which contains a small port 102, and which seats against the 15 end of the plunger 103. The latter passes through a stuffing box in the left hand wall of the diaphragm chamber and is threaded at its outer end to receive an adjustable disk 104. The end of the plunger 103 bears 20 against the end of the gas valve stem 105 which passes through a stuffing box in the front wall of the gas valve body and bears in turn on the gas valve seat 19^a. A spring 106 is also provided in this construction to 25 hold the gas valve seat 19^a normally closed. The end of the thermostat lever 97 is forked and is so shaped as to make engagement on its right hand side with the washer of the spring 98 and also with a threaded nut 107 30 which is held in place against the engaging surface of the thermostat lever by the spring 99. The threaded nut 107 carries an adjustable screw 108, the head of which is opposite the end of a stem 109, which passes 35 through a stuffing box in the left hand wall of the diaphragm chamber 50^a and terminates opposite the port 24^a in the check valve head 110.

The parts are normally adjusted as shown 40 in the figure, so that when the water is at rest and the temperature less than that at which the thermostat control may be set to act the check valve head 110 will be out of contact with its seat—it being forced to the 45 left by the unbalanced pressure of the water on the stem 109—and the nut 104 will be out of contact with the upper end of the thermostat lever 97. With this adjustment the 50 operation of the apparatus shown in Fig. 6 is as follows: When the water is drawn from the heater the pressure in the chamber 96 will be reduced below that in the chamber 5^a by the resistance to the flow of the water through the heater coils, and the ports 10^a 55 and 24^a both being open, the diaphragm 51^a will be forced to the left carrying with it the plunger 103 and the gas valve stem 105, thus opening the gas valve 19^a and admitting fuel to the main burners through the 60 pipe I. As soon as the flow of water is stopped, the pressures in the chambers 5^a and 96 are of course at once equalized and the diaphragm is returned to its normal 65 right hand position by the joint action of the springs 100 and 106, the gas valve 19^a

being simultaneously closed by the latter. If, while the water is flowing the temperature rises above the point for which the thermostat is set, the resultant downward movement of the thermostat element 76 70 allows the springs 98 and 99 to force the thermostat lever 97 to the right far enough to allow the port 24^a to be closed by the action of the parts 107, 108, 109 and 110. The moment that this port is closed the 75 pressures on the two sides of the diaphragm 51 will begin to equalize by reason of the passage of the water from the one side of the diaphragm to the other through the small port 102. This equalization of pressure will allow the diaphragm 51^a to be forced back to the right as before by the pressure of the springs 100 and 106, and the gas valve 19^a will be closed again. This movement of closure can be expedited and 80 rendered more positive by adjusting the nut 104 so that the right hand movement of the thermostat lever 97 will bring the end of said lever into engagement with the face of the nut and force the latter to the right. 85 When the temperature falls again the contraction of the positive member 75 of the thermostat will lift the negative member 76 and will force the thermostat lever 97 to the left, compressing the springs 98 and 99, and 90 successively or simultaneously relieving the pressure on the nut 104 and the check valve head 110. The latter will then be moved to the left by the unbalanced pressure of the water on the stem 109, and the port 24^a again 95 opened, thus putting the left hand side of the diaphragm chamber again in communication with the chamber 96. If the water is still flowing through the heater, the opening of this port will reduce the pressure on the right hand side of the diaphragm 51^a below that on the left hand side, because the water is withdrawn through the port 24^a much more rapidly than it can be supplied through the small port opening 102, and the 100 diaphragm will, in consequence of this, be once more moved to the left, again opening the gas valve 19^a.

Fig. 7 illustrates a variation in the construction shown in Fig. 6. The only difference between these two constructions is that, in the one shown in Fig. 7, the thermostat consists of a single positive element 28^a which acts directly in its expansion upon the thermostat lever 115 moving the latter 115 positively to the right and compressing the spring 116. The outer end of this thermostat lever is threaded to receive an adjustable screw 117 which bears against the head of the plug valve 118 sliding in the port 24^a. The outer end of said thermostat lever 115 is also forked to engage with a collar 119 which is threaded on the plunger 103 which engages at one end the collar 101 at the center of the diaphragm 51^a, and at the 120 125 130

other end with the stem 105 of the gas valve. The nut 119 is prevented from rotation by means of a pin 120 engaging with the slot in the side of the thermostat lever chamber, 5 and the plunger 103 can be rotated so as to vary the position of the nut 119 by means of a milled head 121.

The operation of this thermostat control is the same as that illustrated in Fig. 6, 10 save that the closing of the plug check valve 118, and the positive return of the plunger 103 is effected directly by the expansion of the thermostat member 28⁴, while the reverse movement of the parts is brought about, 15 when the temperature falls, by the pressure on the spring 116.

Construction of Fig. 8.

In this construction 6⁴ is the cold water 20 inlet pipe, which cold water inlet pipe has a branch 7⁴ leading to the upper coil of the heater and corresponding to the pipe 7 in the construction of Figs. 1, 2 and 3. The water valve casing 4⁴ is provided with the 25 pair of ports 10⁴ and 24⁴ corresponding to the ports 10 and 24 in the construction of Fig. 3, such ports being located on opposite sides of the piston 3⁴. The port 24⁴ communicates with the thermostat casing 27⁴ 30 by means of the pipe 122, and the construction of the thermostat parts 75⁴ and 76⁴ correspond to that of the thermostat shown in Fig. 5, the member 76⁴ operating the pair of levers 123 and 124 pivoted as indicated 35 in the drawing, and so arranged that on the heating of the water in the thermostat casing and the expansion of the member 75⁴, the lower end of the lever 124 is caused to move to the left under the influence of the 40 spring 125. The lower end of the thermostat casing 27⁴ communicates with the lower coils of the heater by means of a connection 2⁴, so that on opening the outlet from the casing 27⁴ the hot water from the 45 heater flows through the connection 2⁴ and through the casing 27⁴. Gas supplied to the heater via the pipe G⁴ and I⁴ passes through the gas valve casing and past the valve 19⁴, which gas valve is normally held closed by 50 means of the spring 127. The piston member 3⁴ is provided with a transverse bar 128 rigidly held in position by means of the studs 129, and this bar 128 in turn carries a rod or stem 130 lying in opposition to the 55 stem 131 of the gas valve. Surrounding the stem 130 is a sleeve 132 carrying at each end a valve seat, such seats being designated by the reference numerals 133 and 134. These valve seats or disks 133 and 134 are 60 adapted to seat against the opposite ends of the member 135, such member being provided with the ports 136, 137 and 138, the latter lying in alinement with the port 24⁴. The member 135 when once assembled in 65 the position shown in the drawings, is de-

signed to remain immovably in such position during the operation of the apparatus, and is made separate from the casing 4⁴ primarily in order to permit of the ready assembling of the parts, and to permit of the placing of the sleeve 132 in position. The sleeve 132 and the piston 3⁴ are normally held in the relative position shown by means of the spring 139. The sleeve 132 is adapted to be moved to the left in order 75 to seat the disk 134 and unseat the disk 133 by the tube 140 carrying at its front end a disk 141 adapted to be engaged by the thermostat arm 124 when the temperature of the water in the heater rises above 80 a predetermined point. The spring 142 serves to carry the tube 140 to the right when the lever 124 is permitted to move to the right.

Assuming that the water in the heater is 85 comparatively cold and the parts are in the position as shown in Fig. 8, the operation is as follows. On opening the outlet from the thermostat casing 27⁴ water flows into the heater through the pipes 6⁴ and 7⁴. This 90 operation gives a differential pressure on opposite sides of the piston 3⁴ due to the difference in pressure in the thermostat casing 27⁴ and in the inlet pipe 6⁴, such pressure being communicated to the opposite sides 95 of the piston via the pipe 122 and ports 24⁴ and 138 on the one hand and through the passage 143 and port 10⁴ on the other hand, inasmuch as the seating of the disk 133 upon its seat prevents an equalization of pressure 100 through the annular space outside the sleeve 132. This differential pressure of course causes the piston 3⁴ to move to the right, thus opening the gas valve 19⁴ and permitting 105 a flow of gas to the burners. If, during the outflow of water from the heater, the temperature of the water rises above a predetermined point, the thermostat arm 124 acting under the influence of the spring 125 moves to the left, thus carrying the tube 110 140 to the left. This causes the seating of the disk 134 and the unseating of the disk 133. When the disk 133 is unseated, the pressure on the left side of the piston 3⁴ 115 may be communicated to the other side of the piston via the annular passage-way outside the sleeve 132, and the ports 136 and 137, the seating of the disk 134 at this time preventing any reduction of pressure on the left hand side of the piston. The pressure 120 on the two sides of the piston thus being equalized, it will return to its original position, thus moving the stem 130 to the left and permitting the gas valve 19⁴ to close. This condition is maintained until the temperature of the water drops sufficiently to 125 permit the lever 124 to move to the right, at which time the disk 134 is unseated and the disk 133 seated, and the pressure in the casing is again unbalanced, causing the pis- 130

ton to again open the gas valve. The check valve 8⁴ serves to still further increase the difference in pressure upon the inlet and outlet pipes of the piston, when the outlet 5 from the heater is opened, although, if desired, this check valve may be dispensed with, as the friction of the water passing through the heater will always provide a sufficient difference of pressure between the ther- 10mostat casing 27⁴ and the inlet 6⁴ to secure an operation of the piston, if the piston is made of sufficient diameter, or if the pressure in the water supply main is not reduced very much below its usual value. It 15 will also be understood by those skilled in the art, that I may set up the operating differences in pressure on the two sides of the water actuated piston or diaphragm member in any other of the ways known 20 to those skilled in the art, and that the necessary difference in water pressure potential may be secured by connections to separated points in the system different from the points illustrated. Other changes in mechanical 25 detail not illustrated herein will readily suggest themselves to those skilled in the art.

Having thus described my invention and illustrated its use, what I claim as new and desire to secure by Letters Patent is the following:—

1. In an automatic water heater, a conduit through which the water passes to be heated, and comprising an inlet portion, an outlet portion, and an intermediate heating 35 portion, a burner for heating the said intermediate portion, a gas valve for controlling the supply of gas to the burner, a pair of pressure chambers lying outside the conduit but connected respectively to the inlet and 40 outlet portions whereby a differential pressure is secured in the chambers when the outlet from the heater is open, means actuated by the differential pressure in the chambers for operating the gas valve, a passage-way 45 leading from the conduit to one of the chambers, a thermostat governed by the heated water, and a valve in the said passage-way operated by the thermostat.

2. In an automatic water heater, a conduit through which the water passes to be heated, and comprising an inlet portion, an outlet portion, and an intermediate heating portion, a burner for heating the said intermediate portion, a gas valve for controlling the supply of gas to the burner, a pair of pressure chambers lying outside the conduit but connected to separate portions of the conduit so far removed from each other that the friction of the water in the 55 intermediate portion provides a substantial differential pressure in the two chambers when the outlet is opened, means actuated by the differential pressure in the chambers 60

for operating the gas valve, a passage-way leading from the conduit to one of the chambers, a thermostat governed by the heated water, and a valve in the said passage-way operated by the thermostat. 65

3. In an automatic water heater, the combination of a water heating conduit having supply and discharge connections, a flow resisting member located in said supply connection, a fuel supply valve, a pressure operated motor for governing said fuel valve, said motor having a piston movable therein 70 dividing said motor into two pressure chambers, one of said chambers having communication with said supply connection in advance of said resisting member, a restricted by-pass about said resisting member leading 75 from said supply connection through the other pressure chamber to said discharge connection, a valve governing said by-pass and a thermostat governed by the heated water adapted to control said by-pass valve. 80

4. In an automatic water heater, a combination with a water heating conduit, a flow resisting member located in the conduit, a fuel supply valve, a pressure operated 90 motor for governing said fuel valve, said motor having a pressure actuated member dividing said motor into two pressure chambers, one of said chambers having constant communication with said conduit in advance 95 of the said flow resisting member, a by-pass around the resisting member leading from said conduit through the other pressure chamber to the conduit at a point behind said resisting member, a valve governing said by-pass, and a thermostat governed by the heated water and adapted to control the by-pass valve. 100

5. In an automatic water heater, the combination of a water heating conduit having supply and discharge connections, a flow 105 resisting member located in said supply connection, a fuel supply valve, a pressure operated motor for governing said fuel valve, said motor having a pressure actuated member dividing said motor into two pressure chambers, one of said chambers having communication with said supply connection in advance of said resisting member, a by-pass 110 to said resisting member leading from said supply connection through the other pressure chamber to said discharge connection, a valve governing said by-pass, and a thermostat governed by the heated water adapted to control said by-pass valve. 115

In testimony whereof I have hereunto 120 signed my name in the presence of the two subscribed witnesses,

FRANK L. O. WADSWORTH.
